UNITED STATES PATENT OFFICE.

JOSEPH E. GUAY, OF WHITEHALL, NEW YORK.

IDENTIFICATION DEVICE.

Application filed June 5, 1926. Serial No. 113,975.

This invention relates to identification devices, and has particular reference to an identification appliance particularly adapted for use in connection with safety deposit boxes or the like.

The particular object of the present invention is to provide an appliance for the doors of safety deposit boxes, which in addition to identifying the boxes by number and the name of the holder, will enable the clerk in charge to tell at a glance if the person presenting the key is entitled to access to the box.

The invention furthermore aims to provide an appliance or attachment for the doors of safety deposit boxes which is so constructed as to facilitate the reading of the number of the box and the name of the holder by virtue of the fact that the number and name-bearing surfaces of the boxes appreciably above and below the clerk's line of vision, are disposed at a suitable inclination for the purpose.

The invention furthermore comprehends an identification and indicia-bearing appliance for the doors of safety deposit boxes which exposes to view the number while normally concealing the name of the holder, but upon ready manipulation by the clerk allows for the reading of the name of the holder.

More specifically, the invention comprehends an identification appliance of the character set forth which comprises a base having means for interchangeably supporting name-bearing elements of distinguishing colors, and a cover normally maintained in concealing relation to the name-bearing elements but provided with a portion allowing for the observation of the color of the element.

The invention furthermore seeks to provide a device of the character set forth which is comparatively simple in its construction and mode of use, inexpensive to manufacture, and which is highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications

which properly fall within the scope of said claims may be resorted to when found expedient.

In the drawings—

Figure 1 is a perspective view of the appliance on the door of a safety deposit box;

Figure 2 is a vertical sectional view through the appliance;

Figure 3 is a perspective view of one of the name bearing elements;

Figure 4 is a plan view of the screen with a name bearing card beneath it; and

Figure 5 is a similar view of a portion of the same on an enlarged scale.

Referring to the drawings by characters of reference, the device includes a base 10, which is formed with a front face 11 having a transverse undercut or dove-tailed recess 12 for the reception of a name-bearing element 13, the name-bearing elements to be interchangeably associated with the recess and to be of a distinguishing color for the purpose of denoting whether the rent is due, the box is under court jurisdiction as in the case of the death of the owner, vacant, or any other similar condition, which will readily enable the safety deposit box clerk to tell at a glance whether the person presenting the key is entitled to access to the box. In order to conceal from view the name of the holder or renter of the box, the cover 14 is hinged at 15 to the base and is normally urged by a spring 16 to a closed or covering relation with respect to the face 11. The cover is provided with a slot 17 filled by a screen 18 or other suitable element which will allow for the observation of the color of the card or element 13 while precluding the reading of the name thereon, and, if desired, said screen may have indicia 19 thereon constituting the identification number of the box.

As shown in the drawing, the screen 18 is formed of superimposed V-shaped elements 18^a and 18^b. The elements are oppositely disposed with their apexes overlying one another at the longitudinal center of the screen. By thus constructing the screen, the openings thereof are of different sizes and shapes and are spaced a distance apart so that only such small portions of the letters of the name on the card will be seen, see Figs. 4 and 5, that the reading of the name is effectually prevented while the color of the card can be readily seen. The cover may be provided with a projecting lug or lip 20

to constitute means for swinging the same to an open position so that the clerk may readily observe the name of the holder or renter.

- In practice, for instance where the box is under court jurisdiction, as in the case of death of the owner, the card or name-bearing element 13 may be red; where the box is vacant the name-bearing element may be white; where the rent is due the name-bearing element may be blue, etc., so as to enable the clerk in charge to determine at a glance whether or not the person presenting the key is entitled to immediate access to the box. Furthermore, if the clerk has any doubt as to the authenticity of the person presenting the key, he may check him by asking the name and comparing the same with the name on the name-bearing card 13, by swinging the cover to open position.
- From the foregoing it will thus be seen that a combined safety deposit box number, name plate and information-giving appliance has been devised which will serve to save time and increase the general efficiency in the conduct of the safety deposit business.

What is claimed is:

1. A device of the class described comprising a member carried by the door of a safety deposit box, having means for interchangeably supporting name-bearing cards of distinguishing colors, and a foraminous member overlying the card, said member having spaced apart and diagonally disposed openings whereby the name is obscured and can not be read while the color of the card can be clearly seen.
2. An identification appliance for the doors of safety deposit boxes or the like, comprising a base having means on its front face for the interchangeable reception of name-bearing cards of distinguishing colors,

and a cover maintained in normal closed relation thereto having a slot alined with the card and a foraminous element in said slot having openings diagonally disposed and spaced apart whereby to permit observation of the color of the name-bearing card while preventing the complete reading of the name thereon.

3. An identification appliance for the doors of safety deposit boxes or the like, comprising a base having a recess in its front face for the interchangeable reception of name-bearing cards of distinguishing colors and a cover maintained in normal closed relation to the face of the base having a slot alining with the recess, and a foraminous element covering the slot and bearing the number of the box, the openings of the element being of varying sizes and shapes and spaced from each other, whereby observation of the color of the name-bearing card is permitted, and complete reading of the name thereon prevented.

4. An identification appliance for the doors of safety deposit boxes or the like, comprising a base having a recess in its front face for the interchangeable reception of name-bearing cards of distinguishing colors and a cover maintained in normal closed relation to the face of the base, having a slot alining with the recess, and a foraminous element covering the slot and bearing the number of the box, the openings of the element being of varying sizes and shapes and spaced a distance apart, whereby the observation of the color of the name-bearing card is permitted and the complete reading of the name thereon prevented, the front face of the base and the cover being disposed at an inclination to facilitate the reading of the number and name.

JOSEPH E. GUAY.
